SWITCH CONSTRUCTION

William O. Schultz, South Milwaukee, Wis., assignor to McGraw Electric Company, a corporation of Delaware

Application September 16, 1948, Serial No. 49,512

1 Claim. (Cl. 200—170)

1

This invention relates to switch constructions and is an improvement over that shown in the patent to Steinmayer, No. 1,770,953 of July 22, 1930, for Switch and Operating Mechanism Therefor, assigned to the same assignee as this application.

In switch constructions, as previously made, particularly where the switch was at times required to carry a heavy current, it has been found that the magnetic forces acting on the movable bar or equivalent member of the switch, acts in a manner tending to force the movable bar away from the stationary contacts and thus, due to the slight amount of yield or slack in the operating mechanism holding the bar in place, causes the bar to move away a slight amount from the stationary contacts and thus causes pitting of the movable bar or movable contact and the stationary contacts.

Further than this, in previous switch constructions, the force due to the contact pressure was usually transmitted directly to the connecting rod or actuating rod which moved the connecting bar into and out of engagement with the stationary contact and consequently where it was desired to have heavy contact pressure, it usually was accompanied by a heavy strain placed on the connecting link or operating member.

This invention is designed to overcome the above noted defects and objects of this invention are to provide a novel form of switch which is designed to carry heavy currents, in fact, which is designed to carry exceeding heavy currents for short intervals of time, for instance, surge currents of many thousandths of amperes without disengaging the movable contact members from the stationary contacts and without any pitting or burning whatsoever of either the stationary contacts or the movable contacts.

Further objects are to provide a switch construction which has very high contact pressure and yet which is so made that the force producing the heavy contact pressure is not directly transmitted to the connecting rod or connecting rods, but is much reduced at the connecting rod so that they are not appreciably or materially strained, although this heavy contact pressure is obtained.

Further objects are to provide a novel construction of movable contact and of coacting stationary contacts whereby a rigid, V-shaped stationary contact can be employed and will coact with a tubular and transversely yielding movable contact bar, the side walls of which fit

2

within and contact the side walls of the V-notches of the stationary contacts and yield and thereby maintain a heavy contact pressure, although there may be a slight downward motion of the contact bar in a direction away from the stationary contacts under very severe overload conditions.

Embodiments of the invention are shown in the accompanying drawings, in which:

10 Figure 1 is a transverse view with most of the parts in section showing the switch in closed position.

Figure 2 is a side elevation partly broken away and partly in section showing the construction of Figure 1.

Figure 3 is an enlarged fragmentary view showing the movable contact bar or movable contact of Figures 1 and 2.

Figure 4 is a bottom view of the structure shown in Figure 3, with parts broken away.

Figure 5 is a view corresponding to Figure 4 of a modified form of the invention.

Figure 6 is a line section on the line 6—6 of Figure 3.

25 Figure 7 is a line section on the line 7—7 of Figure 3.

Figure 8 is an end view of one of the stationary contact members and the adjacent portion of the movable contact bar with the remaining portions of the apparatus omitted.

Figure 9 is a fragmentary view showing the lower portion of the connecting link or operating link, such view showing in dotted lines the outline of the movable contact bar.

30 Referring to the drawings, it will be seen that the switch chosen for illustration is a three phase oil switch. It is equipped with a lower tank 1 which may be lined with wood or other insulation 2 and which contains oil to approximately the level indicated by the reference character 3. The tank 1 has bolted thereto an intermediate or head portion 4 and the intermediate or head portion 4 has a cover 5 bolted thereto. Suitable gaskets are provided as indicated and any suitable means for holding the three main portions of the switch together may be employed. It is preferable to provide supporting brackets 6 integral with the head or intermediate portion 4 so that the switch may

40 be attached to a suitable support in the customary manner. It is to be understood that if desired insulating barriers may be interposed between the several sections of the switch as shown, for instance, in the above noted patent, and it 45 is also clear that the same construction herein-
50

after described could be employed for a single phase switch if so desired.

The switch is provided with an operating or rock shaft 7 carried in suitable bearings and extending outwardly from the head portion 4 and provided with an operating handle 8. A plurality of crank arms 9 are rigidly carried by the rock shaft 7 and are connected to spaced brackets 10 secured to channel-shaped cross-head 11 by connecting links 9'. This cross-head 11 is guided in any suitable manner, not shown, for example as indicated in the above noted patent. The cross-head is arranged to simultaneously actuate and impart a vertically reciprocatory motion to a plurality of insulating connecting links or operating links 12. It is preferable to provide straps of generally inverted U-shape as indicated at 13 in Figure 1 at the upper end of connecting links 12. These strips 13 are apertured and receive threaded stems or bolts 14 rigidly carried by the cross-head 11 and upper and lower lock nuts 15 are provided on opposite sides of the bite portion or horizontal portion of the U-shaped members 13 so that each individual connecting or operating link 12 may be separately adjusted for a purpose hereinafter to appear.

The stationary contacts are indicated by the reference character 16 and will be described in greater detail hereinafter. They are rigidly supported by means of insulating bushings 17 and extend through insulating sleeves 18, which bushings and sleeves are located on opposite sides of and secured to a transverse partition or horizontal wall 19 secured to the head 4 as shown most clearly in Figure 1. The partition 19 is suitably apertured and forms a guide for the intermediate portion of the connecting links 12, for instance as has been disclosed in the above noted patent. The stationary contacts 16 are connected to external terminals, not shown, which are located in the insulating bushings 20, by means of conductors or conducting portions 21 bolted as shown to the upper end of the conducting stems 22 of the stationary contacts 16. Suitable insulating hoods 23 are positioned over the exposed members 21 and 22 to thus insure adequate insulation or electrical separation between adjacent portions of the switch in the upper portion of the structure.

The movable contacts or movable bars are indicated generally by the reference character 24 and are carried by the connecting links 12 in a manner to permit a slight movement of the movable contacts 24 with reference to the connecting links 12 so as to allow free seating and adjustment of the movable contacts 24 with reference to the stationary contacts 16 when the switch is closed. It is to be noted at this point also that when the switch is closed, that the connecting links 9' and the operating crank arms 9 form, in effect, toggle link mechanisms and move slightly past dead center until arrested by a suitable stop as set forth in the above noted patent, when the switch is in fully closed position to thereby securely lock the switch closed until released and opened by manipulation of the operating handle 8.

A simple way of connecting the movable contacts 24 to the insulating connecting links 12 is by means of a pair of angular brackets 25 secured to the lower ends of each of the links 12 and connected to the corresponding movable contacts 24 by means of pins 26 extending through downward extensions of the brackets 25. Figure 7 shows the general shape of the brackets 25 and it will be seen from reference to Figure 9 that

each of the brackets 25 is provided with a circular cutaway portion 27 within which the corresponding movable contact 24 is loosely positioned. This contact 24 has a very slight motion permitted it about the pivot pin 26 but nevertheless is held substantially horizontal by coaction with the curved portions or cutaway portions 27 of the brackets 25.

Referring in detail to Figures 3, 4, and 6, it will be seen that the movable contacts 24 are tubular and are formed of two half sections 24' which are spaced apart to provide a slot 28 extending from one end to the other of the tubular, metal movable contact members 24. A pair of rings 29 surround intermediate portions of the tubular contact bar 24 and are provided with rivets 30 which extend loosely through the two half sections 24' of the movable contact bar 24 as shown in Figure 6. These rings limit outward expansion or separation of the two half sections 24' of the tubular contact bar 24. The two half sections are urged apart by springs 31 located adjacent opposite ends of the members 24 and positioned within such members. These springs are provided with a coiled portion 32 and with outwardly turned fingers or ears 33 which loosely fit within apertures 34 formed in the half sections 24' of the contact bars. These springs will hold themselves in a horizontal plane due to the fact that they can secure their greatest expansion or separation of their arms when in this position. They are so made that they exert a heavy force urging the two half sections 24' of the movable contact bars 24 apart.

35 The stationary contacts 16 are provided with V-shaped notches or internal slanting faces 35, see Figure 8, within which the contact bars 24 are drawn when the switch is in closed position as shown in Figure 8.

40 It will be seen from an examination of this figure that the two half sections 24' of the contact bars 24 have been forced towards each other against the opposition of the heavy springs 31. However, in view of the cam action of the slanting faces of the V-shaped notches in the stationary contacts 16, very little resultant force is transmitted to the connecting or operating links 12.

45 It is obvious that the movable contacts may be formed of sufficiently resilient material so that their own resiliency may be relied upon to provide the necessary yield or inward motion of their end portions when they are drawn into the V-shaped notches of the stationary contacts. This form of construction is shown in Figure 5. The movable contact bars are tubular and are indicated by the reference character 36 and are provided with slots 37 cut inwardly from their ends but leaving the center or intermediate portion of the tubular contact bars 36 intact. These contact bars 36 are secured in identically the same manner to the operating or connecting links 12 as previously described. In this last form of the invention it is obvious that when the switch is in closed position and the tubular movable contact bars 36 are drawn upwardly into the V-shaped notches 35 of the stationary contacts 16, that the end portions of these contact bars will be forced towards each other and will thus exert a heavy contact pressure against the side walls of the V-shaped notches of the stationary contacts.

50 It has been found that even with a very heavy overload or short-circuit current that there is no pitting of the stationary contacts or of the movable contacts. Any yield or slackness in the

operating mechanism which would permit a slight downward motion of the movable contacts with reference to the stationary contacts is compensated for by means of the yielding movable, tubular contacts whose half sections are so constructed and arranged that that portion thereof which engages the stationary contacts, in both forms of the invention, will maintain a heavy contact pressure with the side walls of the V-shaped notches of the stationary contacts although the movable contact bars 24 or 36 may have been displaced downwardly a slight amount due to the magnetic effect of the heavy overload current.

If desired, any suitable type of arcing springs or members, for instance, as indicated at 38 may be employed, although these form no part of this invention.

It is to be noted that the collars 29 limit the outward motion or separating motion of the half sections of the contact bar shown in Figures 3 and 4, and that the rivets 30 constitute guides for guiding and holding the two half sections of the bar in alignment with each other.

It is to be noted that the half sections of the bridging bar, see Figure 4, are rigid. Their tubular shape contributes to their rigidity. In spite of their being rigid and in spite of their having solely lateral motion of translation, as distinguished from bending, nevertheless they maintain firm contact with the slanting faces of the stationary contacts and the yielding of the springs allows the half sections to adjust themselves accurately to the slanting faces of the stationary contacts.

It is to be noted also that in both forms of the invention the contact bar has two spaced end portions with a slot between, whether these end portions are separate members from each other as in Figures 3 and 4, or whether they are integrally joined adjacent the central portion of the contact bar as in Figure 5.

Also it is to be noted that in both forms of the invention the half sections or spaced end portions are spring urged laterally whether through the medium of separate spring means or due to the resiliency of the tubular contact bar itself and are arranged to maintain firm engagement with the spaced surfaces of the stationary contacts.

It is to be noted that in both forms of the invention the contact bar or movable contact is, in reality, a bridging bar and bridges the stationary contacts.

It will be seen that a very serviceable and simple type of switch construction has been provided wherein a heavy contact pressure is maintained, although the switch may be heavily overloaded as during short-circuit conditions, for instance, and it will be seen further that this heavy contact pressure is obtained without unduly straining or stressing the connecting links or operating members.

10 Although this invention has been described in considerable detail, it is to be understood that such description is intended as illustrative rather than limiting, as the invention may be variously embodied and is to be interpreted as claimed.

15 I claim:

An electric switch comprising a pair of spaced stationary contacts provided with notches having slanting sides, a movable tubular bridging bar formed of half sections spaced apart by a longitudinal slot, springs within the end portions of said bridging bar for urging said end portions apart into engagement with the slanting sides of the notches of said stationary contacts when said switch is closed, each of said half sections being rigid and having lateral motion of translation, spaced collars surrounding the half sections of said bridging bar and limiting the amount of separation of the half sections when said switch is open, guiding means carried by said collars and slidably supporting said half sections and maintaining alignment of the half sections of said bridging bar, and operating mechanism for moving said bridging bar into switch open and switch closed positions, said operating mechanism being pivotally joined to said bridging bar intermediate the ends of said bridging bar.

WILLIAM O. SCHULTZ.
